UNITED STATES PATENT OFFICE.

CHARLES A. HARVEY, OF CHICAGO, ILLINOIS, ASSIGNOR TO PRODUCER GAS UTILITIES COMPANY, A CORPORATION OF ILLINOIS.

VALVE.

No. 927,794.

Specification of Letters Patent.

Patented July 13, 1909.

Application filed October 12, 1908. Serial No. 457,306.

To all whom it may concern:

Be it known that I, CHARLES A. HARVEY, a citizen of the United States, residing at Chicago, in the county of Cook and State of Illinois, have invented a new and useful Improvement in Valves, of which the following is a specification.

My invention relates to certain new and useful improvements in valves and is fully described and explained in the specification and shown in the accompanying drawing, which is a longitudinal section through my improved valve.

My improved valve is particularly designed for use in connection with gas producers, its object being primarily to provide a simple and efficient, as well as thoroughly safe device, by which the hot gas coming from the producer can be sent to the scrubber for subsequent treatment or at will to the night-stack where it will be dissipated.

Referring to the drawing, A is the intake-pipe of a valve through which the hot gas issues from the producer and this gas enters a **T**-fitting B having two horizontal arms, the lower portion of the **T**-fitting being arched upward at *b* to provide a medial dividing line from which water will tend to flow in both directions.

C is a water intake-pipe through which the overflow water from the scrubber enters the fitting B flowing thence in both directions from the divide.

To the right-hand side of the fitting B is a **T**-fitting D, through which extends a vertical pipe E, the upper end of which communicates with an exhaust-pipe F leading to the night-stack, and the lower end of which is considerably below the upper limit of the divide *b*. The upper end of the pipe E fits the upper end of the **T**-fitting D tightly, by means of a suitable bushing so that the whole may be removed for cleaning if necessary, so as not to permit the egress of gas around the pipe at the upper end. The lower end of the pipe E is surrounded by a considerable space so that the gas can pass downward through the **T**-fitting D and the pipes beneath the same and upward through the pipe E.

Beneath the fitting D and connected therewith by a pipe *d* is a tee G closed at its lower end by a cleaning-plug *g* and connected by a pipe *h* with a three-way cock I, the lower end of which opens into a drain-pipe J.

To the left-hand side of the **T**-fitting B corresponding parts are arranged, that is to say, a **T**-fitting D¹ connected by a pipe *d*¹ with a tee G¹ closed at its lower end by a plug *g*¹, the tee being in turn connected to the opposite side of a three-way cock I by means of a pipe *h*¹. A pipe E¹ is mounted within the **T**-fitting D¹ and extends downward exactly as does the pipe E and the upper end of said pipe E¹ communicates with a pipe F¹ which in practice runs to the scrubber.

From the above description of the construction the operation of the valve will be readily apparent. With the parts in the position shown in the drawing, the water entering through the pipe C will be divided into substantially equal portions and will flow in both directions through the **T**-fittings D, D¹ and down into the tees G, G¹. The water on the right-hand side will meet the closed portion of the three-way cock and will be held back from the drain-pipe thereby and will thus fill up the tee G, the pipe *d* and the **T**-fitting D to the level of the divide *b* in the **T**-fitting B, and thereafter all the water entering through the pipe C will pass out to the left following a similar course to the three-way cock I which, however, will be open to the passage of water from the left-hand side so that the water will flow down the drain. This will leave a free and unobstructed passage for gas in the direction shown by the arrows; that is the gas will enter the **T**-fitting D¹, pass down through the pipe *d*¹, up through the pipe E¹ and through the exhaust-pipe F¹ where it will enter the scrubber and be treated in the usual way. When it is desired to turn the gas into the night-stack the three-way cock I is turned 180° so as to connect the pipe *h* with the pipe J and to obstruct the passage from the pipe *h*¹. The result of this shift will be an immediate emptying of the fitting D, the pipe *d* and the tee G down to the level of the intake to the three-way cock I, so as to leave a passage for gas to the exhaust F and the night-stack, and the water will immediately begin to back up in the tee G¹ ultimately sealing the lower end of the pipe E¹ and preventing the egress of gas to the scrubber.

It will be readily understood that while the valve of my invention has been described particularly for use in connection with producers, for which use it was especially designed, it may find utility in other arts where

gas is to be handled. The construction is particularly desirable for hot gases because the side through which the gas is passing is cooled by the inflowing water constantly 5 while the abutting surface which stops the movement of the gas in the opposite direction is also of water and not liable therefore to injury. It will be evident also, that for reasons of convenience it is desirable to use 10 the valve only in connection with gases under comparatively slight pressure, unless the pipes are made sufficiently large to take care of any flow of gas and unless also, the pressure in the two points to which the gas may be led is substantially equal. The pressure 15 which must be overcome by the gas to flow in the wrong direction is merely that of the head of water from the divide *b* down to the lower end of the pipe E and by varying this 20 distance the capacity of the valve for handling high pressures can be increased within limits, but the length might have to be inconveniently great to withstand a high pressure. The valve is, however, especially 25 advantageous for handling hot gases under comparatively low pressure and in operation it is satisfactory and simple.

I realize that considerable variation is possible in the details of construction of my improved device, without departing from the spirit of my invention, and I do not intend therefore, to limit myself to the specific form herein shown and described.

I claim as new and desire to secure by Letters Patent—

1. The combination with an intake-pipe and two exhaust-pipes, of traps interposed between the intake-pipe and each exhaust pipe, and a single device for at will flooding one 40 trap with water and simultaneously discharging the other trap.

2. The combination with an intake-pipe and two exhaust-pipes, of two traps interposed between the exhaust-pipes and the intake-pipe, means for introducing water in position to flow into both traps, means for drawing off water from the lower portion of each trap and means for at will closing said means in one trap and opening it in the other. 45

3. The combination with an intake-pipe and two exhaust-pipes of traps interposed between the intake-pipe and the exhaust-pipes, means for drawing off liquid from the lower part of each trap, a three-way cock controlling said means whereby the liquid-exit from 50 one trap may be closed and the other simultaneously opened and means for introducing water to flow in such directions as to normally flood both traps.

4. The combination with a T-fitting of an intake-pipe entering the same, means for introducing water to the T-fitting and a water-divide in the T-fitting for shedding water in both directions therefrom, exhaust-pipes, 55 traps interposed between the T-fitting and the exhaust-pipes and means for at will drawing off the water from either trap.

5. The combination with a T-fitting, an intake-pipe opening therein, and a water-pipe also opening therein of vertical members on the two sides of the T-fitting and having communication therewith, pipes leading from the tops of said vertical members and extended downward within the same to form traps therein, means for drawing off liquid 70 from the lower portions of said vertical pipes, and a three-way cock controlling said drawing off. 75

CHARLES A. HARVEY.

In presence of—

CHAS. E. GAYLORD,
RALPH A. SCHAEFFR.
